CLAIM

I claim the ornamental design for a toddler walker, as shown and described.

DESCRIPTION

FIG. 1 is a perspective view of a toddler walker showing the new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

This design is a toddler walker, which may assist a toddler to learn walk and balance.
